[57] ABSTRACT

The L-antipode of 4-methoxy-m-tyrosine and lower alkyl esters thereof which are useful as anti-parkinson agents.

17 Claims, No Drawings

TYROSINE DERIVATIVES

SUMMARY OF THE INVENTION

In accordance with this invention, it has been found that the L-antipode of a compound of the formula:

wherein R is hydrogen or lower alkyl; and pharmaceutically acceptable salts thereof are useful in reducing the symptoms of parkinson disease such as rigor, akinesia and tremor, without causing peripheral adrenergic effects and other undesirable secondary effects.

In accordance with this invention, the L-antipode of formula I can be prepared by resolving a racemic mixture of the compound of formula I above into its optical antipodes and isolating the L-antipode of a compound of formula I above or a pharmaceutically acceptable salt thereof.

On the other hand, the compound of formula I can be prepared from a compound of formula:

wherein R₁ is an amino group protected by a conventional amino protecting group convertible to an amino group; R₂ is hydroxy or hydroxy protected by a conventional hydroxy protecting group convertible to a hydroxy group; R₃ is carboxy or a conventional carboxy protecting group convertible to a carboxy group; or a pharmaceutically acceptable salt thereof, by simultaneously, or any sequence, converting the protected amino group into free amino groups, converting the protected hydroxy group into free hydroxy groups, and/or converting the protected carboxy group into the free acid. The free acid can, if desired be converted into its salt form.

DETAILED DESCRIPTION

As used throughout this application, the term "lower alkyl" designates both straight chain and branched chain alkyl groups containing from 1 to 7 carbon atoms such as methyl, ethyl, isopropyl, n-hexyl, etc. Among the preferred alkyl groups are included methyl and ethyl.

The compounds of formula I above are amphoteric in character. These compounds dissolve in water as well as in acids or in alkalies in which they form salts.

In accordance with this invention, the compounds of formula I with their pharmaceutically acceptable salts exhibit the aforementioned beneficial therapeutic properties. The compounds of formula I form a pharmaceutically acceptable salt, with both inorganic and organic pharmaceutically acceptable acids as well as bases. Among the acids which the compounds of formula I form pharmaceutically acceptable acid addition salts are included, e.g., hydrochloric acid, hydrobromic acid, sulfuric acid, phosphoric acid, citric acid, acetic

acid, succinic acid, maleic acid, methanesulfonic acid, p-toluenesulfonic acid and the like. Such acid addition salts are also within the scope of the invention. Among the bases with which the compounds of formula I form salts are the alkali metal bases such as sodium hydroxide, potassium hydroxide, etc., and ammonia.

The resolution of the racemate of formula I to produce the L-antipode of formula I can be carried out by conventional methods of resolving racemic mixture. For example, a racemic ester of formula I can be resolved using optically active acids such as camphorsulfonic acid, tartaric acid or tartaric acid-2,4-dichloro anilide. The resolution of a racemic free acid of formula I can be carried out using optically active bases such as ephedrine, dehydroabietylamine or the like, as well as optically active acids such as camphorsulfonic acid.

The isolation of the desired L-antipodes can be carried out by conventional isolation methods such as crystallization of the salts and decomposition thereof.

In accordance with this invention, R₁, in the compound of formula II can be any conventionally protected amino group. Among the conventional amino protecting groups are those which can be removed by hydrogenolysis or hydrolysis. Examples of protected amino groups which are convertible into the free amino group (R₁ in the starting materials of formula II) are the following:

25 30 A. Groups which are convertible into the free amino group by hydrolysis such as, for example, lower alkanoylamino groups, the formylamino group, the benzoylamino group and the tertbutoxycarbonylamino group. The formylamino group, the lower alkanoylamino groups, especially the acetoamino group, and the benzoylamino group are preferred.

The hydrolysis of these groups can be carried out in a manner known per se with acids, especially with strong mineral acids such as with aqueous hydrochloric acid or sulfuric acid. The hydrolysis can be carried out at room temperature, but it is preferably carried out at an elevated temperature up to the boiling point of the mixture.

35 45 B. Groups which are convertible into the free amino group by hydrogenolysis such as, for example, the benzoyloxycarbonylamino group or the dibenzylamino group.

Any conventional method of hydrogenolysis can be utilized to remove these groups. For example, hydrogenolysis can be carried out by hydrogenation in the presence of a hydrogenation catalyst. As catalysts there can be used, for example, palladium/charcoal catalysts or platinum catalysts, in which case the hydrogenolysis is expediently carried out in a lower alkanecarboxylic acid such as glacial acetic acid or in a lower alkanol such as methanol or ethanol. Aqueous alkanols may also be used.

50 55 C. Groups such as, for example, the o- or p-nitrophenylthioamino group which can be converted into the free amino group by treatment with acid, for example with aqueous hydrochloric acid, preferably in the presence of thiophenol.

In accordance with this invention, R₂ in the compound of formula II can be any conventional hydroxy protecting group. Among these protecting groups are the protecting groups which can be removed by hydrogenolysis or hydrolysis. Examples of groups which are

convertible into the hydroxy group (R_2 in the starting materials of formula II) are the following:

D. Groups which are convertible into the hydroxy group by hydrolysis such as, for example, lower alkanoyloxy groups, especially the acetoxy group, the formyloxy group and the benzyloxy group.

The hydrolysis of these groups can be carried out by conventional hydrolysis techniques such as with alkalies (e.g., with aqueous or aqueous-alcoholic sodium hydroxide or potassium hydroxide) or with acids (e.g., aqueous hydrochloric acid or sulfuric acid). The hydrolysis can be carried out at a temperature from about 0°C. up to the boiling point of the mixture.

Further, R_2 can represent an etherified hydroxy group such as a methoxy-methoxy group or a tetrahydropyranloxy group which can be converted into the hydroxy group by hydrolysis with acids (e.g., with aqueous hydrochloric acid).

E. Groups which are convertible into the hydroxy group by hydrogenolysis such as, for example, the benzyloxy group.

The hydrogenolysis of this group can be carried out in a manner set forth hereinbefore. Among the preferred methods of hydrogenolysis is by treating the compound of formula II with hydrogen in the presence of a hydrogenation catalyst. As catalysts there can be used, for example, palladium/charcoal catalysts or platinum catalysts.

F. The diazonium group which can be converted into the hydroxy group by boiling with aqueous acid, especially with aqueous mineral acid such as sulfuric acid.

In accordance with this invention, R_3 in the compound of formula II can be any conventional carboxylic acid protecting group. Among the preferred protecting groups are the groups which can be removed by either hydrolysis or hydrogenolysis. Examples of groups which are convertible into the carboxyl group (R_3 in the starting materials of formula II) are the following:

G. Groups which are convertible into the carboxyl group by hydrolysis such as, for example, lower alkoxy-carbonyl groups (especially the methoxycarbonyl and ethoxycarbonyl groups) and amide groups; that is to say, amide groups derived from the free amino group and from primary or secondary amides such as the carbamoyl group and mono- or di-alkyl- or aryl-substituted carbamoyl groups, in which case the alkyl groups can contain from 1 to 7 carbon atoms and the aryl group is especially the phenyl group.

A further group which is convertible into the carboxyl group in a manner known per se is the cyano group.

The hydrolysis of the foregoing groups can be carried out according to conventional hydrolysis techniques using acids or bases.

H. Groups which are convertible into the carboxyl group by hydrogenolysis such as, for example, the benzyloxycarbonyl group.

The hydrogenolysis of such a group can be carried out in an analogous manner to the hydrogenolysis methods described hereinbefore.

The conversion of a protected amino group R_1 to the free amino group and the conversion of a group which may be present which is convertible into the hydroxy group or into the carboxyl group (R_2 and R_3) into the

hydroxy group or into the carboxyl group can be carried out in any desired sequence or simultaneously.

If desired, a free acid obtained can be converted into a lower alkyl ester (R represents a lower alkyl group). 5 This can be carried out by conventional esterification techniques such as using the usual esterification agents (e.g., an appropriate lower alkanol).

Furthermore, bases obtained can be converted into salts if desired; the L-antipodes of the free amino acid 10 of formula I forming both acid addition salts and metal salts. Examples of acid addition salts are those with inorganic acids such as hydrochloric acid and those with organic acids such as oxalic acid. Examples of metal salts are, in particular, the alkali metal salts.

15 The preferred starting materials of formula II are those in which R_1 represents a lower alkanoalamino group, especially the acetamino group, the formylamino group or the benzoylamino group.

Another group of preferred starting materials of formula II comprises those in which R_2 represents the hydroxy group, the formyloxy group or a lower alkanoyloxy group, especially the acetoxy group.

20 A further preferred group of starting materials of formula II comprises those in which R_3 represents the carboxyl group or a lower alkoxy-carbonyl group, especially the methoxycarbonyl group or the ethoxycarbonyl group.

The starting materials of formula II are, in part, known and, in part, new.

25 The new starting materials, namely the L-antipodes of compounds of the general formula:

wherein R_1 and R_3 are as above;

and R_2' is formyloxy or lower alkanoyloxy; and their salts, can be prepared by oxidizing the L-antipode of a compound of the general formula:

wherein R_1 and R_3 are as above;

and R_2'' is formyl or lower alkanoyl; with a peracid.

40 As peracids there can be used organic peracids, especially peralkanecarboxylic acids such as peracetic acid, performic acid, trifluoroperacetic acid and the like, the oxidation being preferably carried out in a lower alkanecarboxylic acid such as formic acid and acetic acid. Aromatic percarboxylic acids such as m-chloroperbenzoic acid can also be used as the peracid, in which case the oxidation is expediently carried out in an organic solvent such as methylene chloride or chloroform. The oxidation with a peracid is expediently carried out at a temperature of about 0°C. to about 50°C.

45 The L-antipode of a compound of formula II-B obtained by the foregoing oxidation can subsequently be converted into corresponding compounds wherein R_2' represents the hydroxy group by mild alkaline hydrolysis. This hydrolysis can be carried out, for example,

with aqueous sodium hydroxide or potassium hydroxide at room temperature. If an excess of caustic alkali is used, an alkoxy carbonyl group R_3 can be simultaneously hydrolyzed to the carboxyl group.

The hydrolysis of a compound of formula II-B with conversion of a formyloxy group R_2' into a hydroxy group can also be carried out by mild acidic hydrolysis, for example, with aqueous hydrochloric acid at room temperature or by Kieselgel chromatography.

The known starting materials of formula II can be prepared in an analogous manner (peracid oxidation and subsequent mild hydrolysis).

The compounds of formula III can in turn be obtained from a compound of the formula:

wherein R_1 and R_3 are as above.

Compounds of formula III where R_2'' is formyl can be obtained, for example, by reacting the compound of formula IV above with a formylation agent in the presence of a Lewis acid. Any conventional method of formylation can be utilized to prepare the compound of formula III where R_2'' is formyl. Among the formylation agents there can be used, for example, a formic acid ester, an orthoformic acid ester, formyl chloride, a dihalomethyl lower alkyl ether, especially a dichloromethyl lower alkyl ether such as dichloromethyl methyl ether, hydrocyanic acid, dimethylformamide or other amides of formic acid. This reaction can take place in the presence of any conventional Lewis acid. As the Lewis acid there can expediently be used a zinc halide such as zinc chloride, an aluminum halide such as aluminum chloride, a titanium halide such as titanium tetrachloride, an iron trihalide such as iron trichloride or a tin halide such as tin tetrachloride.

The formylation reaction can be carried out in the absence of a further solvent if the formylation agent is used in excess. On the other hand, the formylation reaction can also be carried out in the presence of an inert organic solvent (e.g., nitrobenzene, carbon tetrachloride, methylene chloride or chloroform). The reaction temperature can vary within a very wide range. Generally, it is preferred to use a temperature of from about -50°C . and the reflux temperature of the reaction mixture.

Compounds of formula III in which R_2'' represents a lower alkanoyl group (e.g., the acetyl group) can be obtained, for example, by reacting the compound of formula IV with a functional derivative of a lower alkanecarboxylic acid (e.g., acetic acid) in the presence of a Friedel-Crafts catalyst. As the Friedel-Crafts catalyst there can be used especially a strong Lewis acid; for example, boron trifluoride, an aluminum trihalide (e.g., aluminum trichloride), a titanium tetrahalide (e.g., titanium tetrachloride) or an iron trihalide (e.g., iron trichloride). Any conventional reactive functional derivative of a lower alkane carboxylic acid can be used in this reaction. As the functional derivatives of the lower alkane carboxylic acids there are especially used acid halides (e.g., acetyl chloride). The reaction is expediently carried out in an organic solvent (e.g., nitrobenzene) at a temperature between about 0° and 200°C .

The present invention is also concerned with pharmaceutical preparations having anti-parkinson activity.

The pharmaceutical preparations provided by the present invention contain as an essential active ingredient the L-antipode of a compound of formula I or a pharmaceutically acceptable salt thereof in combination with a compatible pharmaceutical carrier.

On administration of such a preparation, the typical symptoms of idiopathic parkinsonism such as rigor, akinesia and tremor can be significantly improved or abolished without peripheral adrenergic effects and other undesirable secondary effects thereby occurring.

The compounds of formula I and their salts can be used as medicaments; for example, in the form of pharmaceutical preparations which contain them in association with a compatible pharmaceutical carrier which can be an organic or inorganic inert carrier material suitable for enteral or parenteral administration such as, for example, water, gelatin, gum arabic, lactose, starches, magnesium stearate, talc, vegetable oils, polyalkylene glycols, petroleum jelly, etc. The pharmaceutical preparations can be made up in solid form (e.g., as tablets, dragees, suppositories or capsules) or in liquid form (e.g., as solutions, suspensions or emulsions). The preparations may be sterilized and/or may contain adjuvants such as preserving, stabilizing, wetting or emulsifying agents, salts for varying the osmotic pressure or buffers. They can also contain other therapeutically valuable substances.

In comparison the L-dopa, a known anti-parkinson agent, the active ingredients aforesaid (i.e., the compounds of formula I or salts thereof) and the pharmaceutical preparations provided by the present invention possess a depot action (half-life 4-5 hours). The LD_{50} in the mouse amounts to more than 5,000 mg./kg. p.o. in the 24-hour test. On administration of the pharmaceutical preparations provided by the present invention, the undesirable secondary effects which usually appear on administration of L-dopa, namely gastrointestinal complaints, involuntary movements and circulatory complaints, do not occur or only occur to a very slight extent.

The pharmaceutical preparation provided by the present invention can be made up in solid or liquid form and, in addition to the essential active ingredient, can contain suitable pharmaceutical organic or inorganic carrier materials such as water, gelatin, lactose, magnesium stearate, talc or the like. The pharmaceutical preparations can be made up in solid forms such as tablets, dragees or capsules or in liquid forms such as solutions, suspensions or emulsions. Tablets are preferred.

A pharmaceutical preparation in dosage unit form can expediently contain about 50 mg. to about 1,000 mg., preferably about 500 mg. to about 1,000 mg. of active ingredient.

The pharmaceutical preparations can also contain one or more peripheral decarboxylase inhibitors, whereby a reduction of the amount of active ingredient to be administered is made possible. As the decarboxylase inhibitor there can be used any pharmaceutically tolerable substance which inhibits the decarboxylase in the extracerebral organs and thereby prevents the de-carboxylation of the active ingredient in these organs.

For this purpose there can be used as the decarboxylase inhibitor a compound of the general formula:

wherein R is a hydrogen, amino-(lower alkanoyl), amino-(hydroxy lower alkanoyl); and n is an integer from 2 to 3; or a pharmaceutically acceptable salt thereof.

For example, there can be used as the decarboxylase inhibitor:

$\text{N}^1\text{-D,L-seryl-N}^2\text{-(2,3,4-trihydroxybenzyl)-hydrazide}$;

$\text{N}^1\text{-L-seryl-N}^2\text{-(2,3,4-trihydroxybenzyl)-hydrazide}$;

$\text{N}^1\text{-glycyl-N}^2\text{-(2,3,4-trihydroxybenzyl)-hydrazide}$;

$\text{N}^1\text{-D,L-tyrosyl-N}^2\text{-(2,3,4-trihydroxybenzyl)-hydrazide}$; or

$\text{N}^1\text{-L-tyrosyl-N}^2\text{-(2,3,4-trihydroxybenzyl)-hydrazide}$; or a pharmaceutically acceptable salt of one of these compounds.

Other suitable decarboxylase inhibitors are, for example, benzylideneacetophenone, $\text{L-3-(3,4-dihydroxyphenyl)-2-methyl-alanine}$ and compounds of the general formula:

wherein Q is hydrogen or lower alkyl; as well as 3,4-dihydroxy-benzylxyamine and salts thereof.

Where the present pharmaceutical preparations contain a decarboxylase inhibitor, the weight ratio of active ingredient to decarboxylase inhibitor expediently amounts to about 5:1 to 10:1.

The pharmaceutical preparations provided by the present invention can be manufactured by mixing the L-antipode of a compound of formula I or a pharmaceutically acceptable salt thereof, if desired together with a peripheral decarboxylase inhibitor, with a compatible pharmaceutical carrier material suitable for medicinal administration. As the carrier material there can be used the carrier materials which are usual in pharmacy.

In the manufacture of dosage unit forms of the present pharmaceutical preparations there are preferably used about 50 mg. to about 1,000 mg., preferably about 500 mg. to about 1,000 mg. of active ingredient per dosage unit.

If the present pharmaceutical preparations are to additionally contain a decarboxylase inhibitor, such can be admixed with the active ingredient and/or the carrier materials or such a preparation can be manufactured by incorporating the active ingredient into a core, providing this with a coating which is resistant to gastric juice and applying thereover an external layer which contains the decarboxylase inhibitor. In this manner there is provided a pharmaceutical preparation from which the active ingredient is released with delay only after the decarboxylase inhibitor has been released, preferably about 30 to 60 minutes after the decarboxylase inhibitor. This has been found to be especially expedient. In the case of parenteral administra-

tion, the decarboxylase inhibitor is expediently administered first, expediently intravenously, and the active ingredient is administered about 30 to 60 minutes later.

5 In the treatment of Parkinsonism, the active ingredient, optionally in combination with a peripheral decarboxylase inhibitor, can be administered either orally or parenterally, especially intravenously.

10 The amount of active ingredient to be administered per day is governed by the particular case.

In general, in the case of oral administration, an amount of active ingredient of about 1.5 to about 4 g. especially about 3 g., will be employed. In the case of intravenous administration, the amount of active ingredient to be administered per day can lie between about 15 50 mg. and about 2 g., especially at about 1 g.

The foregoing amounts relate to the active ingredient content calculated as 4-methoxy-L-m-tyrosine which represents a preferred active ingredient in accordance 20 with the present invention.

As has already been mentioned, the amount of active ingredient administered can be reduced by the combined administration thereof with a peripheral decarboxylase inhibitor. In the case of such a combined administration, there are expediently used amount of active ingredient which lies in the lower part of the foregoing ranges. For example, 1 g. of active ingredient and 100 mg. of a decarboxylase inhibitor (ratio 10:1 parts by weight) or 500 mg. of active ingredient and 100 mg. of decarboxylase inhibitor (ratio 5:1 parts by weight) can be administered orally per day.

The administration is expediently effected in individual doses divided over the day.

35 The following examples are illustrative but not limitative of the invention. All temperatures are in degrees centigrade. 40 percent peracetic acid refers to percent by weight. The term "concentrated hydrochloric acid" refers to a hydrogen chloride content of 38 percent by weight.

EXAMPLE 1

A mixture of 5.3 g. (19.9 mmol) of N-acetyl-4-methoxy-L-m-tyrosine methyl ester and of 100 ml. of 3-N aqueous hydrochloric acid is heated at reflux in an argon atmosphere for 2 hours. The 4-methoxy-L-m-tyrosine hydrochloride crystallizes out on concentration of the solution under reduced pressure. Yield: 3.3 g.; melting point 247°-247.5°C.; $[\alpha]_D^{25} = -12.75^\circ$ ($c = 4$ percent in water).

EXAMPLE 2

3.3 g. (13.3 mmol) of 4-methoxy-L-m-tyrosine hydrochloride are dissolved in 150 ml. of ethanol and 12.5 ml. of propylene oxide are added to the solution in several portions in the course of 3 hours. The mixture is then left to stand at 25°C. for 20 hours and the precipitated crystals are filtered off. The pure 4-methoxy-L-m-tyrosine is obtained by one recrystallization from 40 ml. of absolute ethanol to which a few drops of water are added. Yield: 2.15 g.; melting point 251°-252°C.; $[\alpha]_D^{25} = -34.2^\circ$ ($c = 1$ percent in water).

EXAMPLE 3

65 A solution of 27.9 g. (0.1 mol) of N-acetyl-3-(3-formyl-4-methoxyphenyl)-L-alanine methyl ester, 20 g. of 40 percent peracetic acid in glacial acetic acid and

150 ml. of glacial acetic acid is left to stand at 25°C. for 23 hours and then evaporated under reduced pressure. 200 ml. of saturated aqueous sodium hydrogen carbonate solution are added to the residue and it is extracted twice with 250 ml. of ethyl acetate each time. The extracts are combined, dried over sodium sulphate and evaporated. The residue consists of a mixture of N-acetyl-4-methoxy-L-m-tyrosine methyl ester and its formate, i.e., N-acetyl-3-(3-formyloxy-4-methoxyphenyl)-L-alanine methyl ester. The hydrolysis of the formate to N-acetyl-4-methoxy-L-m-tyrosine methyl ester is completed by chromatography of this mixture on a column containing 3,000 g. of silicagel [elution with ethyl acetate/toluene (1:1 parts by volume)] and 16.8 g. (63 percent) of the desired compound are obtained after one recrystallization from ethyl acetate/ether. Melting point 97°-98°C.; $[\alpha]_D^{25} = +31.5^\circ$ ($c = 2$ percent in 95 percent ethanol).

EXAMPLE 4

167 ml. of titanium tetrachloride are added with stirring in the course of 5 minutes to a solution of 95 g. of N-acetyl-3-(p-methoxyphenyl)-L-alanine methyl ester in 1500 ml. of nitrobenzene, the temperature rising to 38°C. The mixture is cooled to +23°C., 69.4 ml. of dichloromethyl methyl ether are then added in the course of 3 minutes and the mixture is stirred at room temperature for 2 hours. The solution is cooled to +5°C. and poured with stirring into 380 ml. of ice-cold 3-N aqueous hydrochloric acid. 4,000 ml. of ethyl acetate and 2,000 ml. of tetrahydroduran are added, the mixture is neutralized by the introduction with stirring of 1,200 g. of anhydrous potassium carbonate and dried over sodium sulphate. After filtration, the filtrate is evaporated (finally in a high vacuum at 70°C.). The residue is dissolved in 500 ml. of methylene chloride and applied to a chromatographic column containing 200 g. of silicagel. Elution with ethyl acetate/methylene chloride (1:1; v/v) yields, after evaporation, 72 g. of N-acetyl-3-(3-formyl-4-methoxyphenyl)-L-alanine methyl ester which can be further purified by recrystallization from ethyl acetate/hexane.

EXAMPLE 5

The N-acetyl-3-(p-methoxyphenyl)-L-alanine methyl ester can be obtained by esterification with methanol of the corresponding free acid by the procedure given in Example 9 hereinafter.

EXAMPLE 6

By the procedure described in Examples 1 and 2, 4-methoxy-L-m-tyrosine and its hydrochloride are obtained from N-acetyl-4-methoxy-L-m-tyrosine ethyl ester [melting point 119°-120°C.; $[\alpha]_D^{25} = +25.4^\circ$ ($c = 2$ percent in 95 percent ethanol)].

EXAMPLE 7

The N-acetyl-4-methoxy-L-m-tyrosine ethyl ester can be obtained by the procedure described in Example 3 (oxidation with peracetic acid in glacial acetic acid and hydrolysis) from N-acetyl-3-(3-formyl-4-methoxyphenyl)-L-alanine ethyl ester [melting point 100°-101°C.; $[\alpha]_D^{25} = +24.0^\circ$ ($c = 1.0$ percent in 95 percent ethanol)].

EXAMPLE 8

The N-acetyl-3-(3-formyl-4-methoxyphenyl)-L-alanine ethyl ester is obtained by the procedure de-

65

scribed in Example 4 by formylation of N-acetyl-3-(p-methoxyphenyl)-L-alanine ethyl ester [melting point 93°-94.5°C.; $[\alpha]_D^{25} = +23.3^\circ$ ($c = 1.0$ percent in 95 percent ethanol)].

10

5

EXAMPLE 9

Dry hydrogen chloride gas is led into a solution of 160 g. of N-acetyl-3-(p-methoxyphenyl)-L-alanine in 1,600 ml. of absolute ethanol until the solution is saturated, the temperature of the solution being held at 20°-22°C. by cooling (duration 2.5 hours). The solution is then evaporated under reduced pressure, the residue taken up in ethyl acetate, the solution obtained washed with saturated aqueous sodium hydrogen carbonate solution, dried over sodium sulphate and then again evaporated under reduced pressure. The crystalline residue is recrystallized from a mixture of ethyl acetate and hexane. Pure N-acetyl-3-(p-methoxyphenyl)-L-alanine ethyl ester is thus obtained.

EXAMPLE 10

By the procedure described in Examples 1 and 2, 4-methoxy-L-m-tyrosine and its hydrochloride are obtained from N-acetyl-4-methoxy-L-m-tyrosine [melting point 134°-135°C.; $[\alpha]_D^{25} = +55.7^\circ$ ($c = 2$ percent in 95 percent ethanol)].

EXAMPLE 11

A solution of 30 g. of N,O-diacetyl-4-methoxy-L-m-tyrosine in 125 ml. of 5-N sodium hydroxide is left to stand at 25°C. for 20 minutes, then acidified to pH 2.0 with concentrated aqueous sulphuric acid and extracted twice with 250 ml. of ethyl acetate each time. The extracts are washed with 25 ml. of saturated aqueous sodium chloride solution, then dried with sodium sulphate and evaporated under reduced pressure. Pure N-acetyl-4-methoxy-L-m-tyrosine is obtained by recrystallization of the crystalline residue from ethyl acetate.

EXAMPLE 12

47.4 g. of N-acetyl-3-(p-methoxyphenyl)-L-alanine are added to a solution of 80 g. of anhydrous aluminium chloride in 200 ml. of nitrobenzene. The solution thus obtained is cooled to +14°C. and then, without further cooling, 45 ml. of acetyl chloride are added in one portion with stirring. The temperature rises immediately to 29°C. After 20 minutes, the solution is poured onto a mixture of 10 ml. of concentrated aqueous hydrochloric acid and 400 g. of ice. The mixture is extracted twice with 400 ml. of ethyl acetate each time. The extracts are washed twice with 100 ml. of saturated aqueous sodium chloride solution each time, then dried over sodium sulphate and concentrated to a volume of about 600 ml. under reduced pressure. Crystallization occurs on cooling this solution to 0°C. The solution is filtered, the crystals washed with ethyl acetate and dried under reduced pressure. Pure N-acetyl-3-(3-acetyl-4-methoxyphenyl)-L-alanine is thus obtained. Yield: 41 g. Melting point 159°-160°C.; $[\alpha]_D^{25} = +52.5^\circ$ ($c = 2$ percent in 95 percent ethanol).

EXAMPLE 13

A solution of 29.2 g. of N-acetyl-3-(3-acetyl-4-methoxyphenyl)-L-alanine in 40 g. of 40 percent peracetic acid in glacial acetic acid is held at a tempera-

ture of 30°C. for 2.5 hours by cooling at the beginning and warming somewhat towards the end. N,O-diacetyl-4-methoxy-L-m-tyrosine is obtained by evaporation of the solution in a vacuum. Yield 30.9 g.

EXAMPLE 14

4.38 ml. of titanium tetrachloride are rapidly added dropwise to a suspension of 2.37 g. of N-acetyl-3-(p-methoxyphenyl)-L-alanine in 40 ml. of nitrobenzene, the temperature rising to 40°C. and there resulting a dark-brown solution. The solution is cooled to 30°C., 1.82 ml. of dichloromethyl methyl ether are added dropwise in the course of 10 minutes and the mixture is stirred for 20 minutes. The mixture is then poured onto 20 ml. of ice-cold aqueous solution 5 percent by weight of hydrochloric acid and extracted three times with 150 ml. of ethyl acetate each time. The product is isolated from the ethyl acetate phase by extraction with aqueous sodium bicarbonate solution, acidification of the extract with concentrated aqueous hydrochloric acid and renewed extraction with ethyl acetate. The extract is dried over sodium sulphate and evaporated under reduced pressure. Pure N-acetyl-3-(3formyl-4-methoxyphenyl)-L-alanine is obtained by recrystallization of the residue from ethyl acetate. Yield: 0.8 g. Melting point 129°-130°C.; $[\alpha]_D^{25} = +56.0^\circ$ ($c = 2.0$ percent in 95 percent ethanol).

EXAMPLE 15

A solution of 26.5 g. (0.1 mol) of N-acetyl-3-(3-formyl-4-methoxyphenyl)-L-alanine, 20 g. of 40 percent peracetic acid in glacial acetic acid and 150 ml. of glacial acetic acid is left to stand at room temperature for 23 hours and then evaporated under reduced pressure. The residue consists of a mixture of N-acetyl-4-methoxy-L-m-tyrosine and its formate, i.e., acetyl-3-(3-formyloxy-4-methoxyphenyl)-L-alanine. This mixture is dissolved in 100 ml. of 3-N aqueous sodium hydroxide in order to complete the hydrolysis of the formate to N-acetyl-4-methoxy-L-m-tyrosine. The solution is left to stand at 25°C. for 10 minutes, then acidified to pH 2.0 with 6-N aqueous sulphuric acid and extracted with ethyl acetate. The extract is dried over sodium sulphate and evaporated. One recrystallization of the residue from ethyl acetate yields N-acetyl-4-methoxy-L-m-tyrosine. Yield: 18 g. Melting point 134°-135°C.; $[\alpha]_D^{25} = +55.7^\circ$ ($c = 2$ percent in 95 percent ethanol).

EXAMPLE 16

A solution of 8.3 g. (30 mmol) of N-acetyl-4-methoxy-L-m-tyrosine ethyl ester in 50 ml. of 3-N sodium hydroxide is left to stand at 25°C. for 0.5 hour, then acidified to pH 2.0 with 6-N aqueous sulphuric acid and extracted with ethyl acetate. The extract is dried over sodium sulphate and evaporated. One recrystallization from ethyl acetate yields pure N-acetyl-4-methoxy-L-m-tyrosine.

EXAMPLE 17

4-Methoxy-L-m-tyrosine is obtained by the procedure described in Example 1 and Example 2, there being used, instead of N-acetyl-4-methoxy-L-m-tyrosine methyl ester or N-acetyl-4-methoxy-L-m-tyrosine ethyl ester, N,O-diacetyl-4-methoxy-L-m-tyrosine ethyl ester.

EXAMPLE 18

A solution of 32.2 g. of N-acetyl-3-(3-acetyl-4-methoxyphenyl)-L-alanine ethyl ester in 40 g. of 40 percent peracetic acid in glacial acetic acid is held at a temperature of 30° for 2.5 hours by cooling at the beginning and warming somewhat towards the end. N,O-diacetyl-4-methoxy-L-m-tyrosine ethyl ester is obtained by evaporation of the solution under reduced pressure.

EXAMPLE 19

5.3 g. of N-acetyl-3-(p-methoxyphenyl)-L-alanine ethyl ester are added to a solution of 10.7 g. of aluminum chloride in 80 ml. of nitrobenzene. The solution thus obtained is cooled to +19°C. and then, without further cooling, 3 ml. of acetyl chloride are added in one portion with stirring. The temperature rises immediately to 26°C. After 15 minutes, the solution is 20 poured onto a mixture of 10 ml. of concentrated aqueous hydrochloric acid and 50 g. of ice. The mixture is extracted twice with 150 ml. of ethyl acetate each time. The extracts are washed once with 50 ml. of water and twice with 50 ml. of saturated aqueous sodium hydrogen carbonate solution each time, then dried over sodium sulphate and evaporated under reduced pressure. Pure N-acetyl-3-(3-acetyl-4-methoxyphenyl)-L-alanine ethyl ester is obtained by one recrystallization of the crystalline residue from a mixture of ethyl 25 acetate and diethyl ether. Yield: 4.0 g. Melting point 90°-92°C.; $[\alpha]_D^{25} = 22.9^\circ$ ($c = 2.0$ percent in 95 percent ethanol).

EXAMPLE 20

35 By the procedure described in Examples 1 and 2, 4-methoxy-L-m-tyrosine is obtained by the hydrolysis of 0-acetyl-N-formyl-4-methoxy-L-m-tyrosine. Instead of 0-acetyl-N-formyl-4-methoxy-L-m-tyrosine there can also be used N-formyl-4-methoxy-L-m-tyrosine which can, in turn, be obtained by hydrolysis of the 0-acetyl compound in accordance with the procedure described in Example 11.

40 The 0-acetyl-N-formyl-4-methoxy-L-m-tyrosine can, in turn, be obtained by the procedure described in Example 15 by the peracid oxidation of 3-(3-acetyl-4-methoxyphenyl)-N-formyl-L-alanine which, in turn, can be obtained by the procedure described in Example 12 from N-formyl-4-methoxy-L-phenylalanine.

EXAMPLE 21

55 A mixture of 200 g. of N-benzoyl-4-methoxy-L-m-tyrosine [Helv. 35, 1776 (1952)] and 2,000 ml. of 3-N aqueous hydrochloric acid is heated at reflux with stirring in an argon atmosphere for 15 hours and then cooled. The mixture is then extracted twice with 500 ml. of benzene each time. The organic phases are washed twice with 200 ml. of water each time. The combined aqueous extracts are evaporated at 50°C./12 mm Hg.

60 The residue is dissolved in 500 ml. of water and, after the addition of 10 g. of active charcoal, heated to 70°C. for 10 minutes. The hot solution is filtered, washed with 100 ml. of water and the filtrate evaporated under reduced pressure.

65 The residue is dissolved in a small amount of water while gassing with argon, then adjusted to pH 4.5 to 5 by the addition of sodium carbonate and then cooled

to 0°C. for 12 hours. The precipitated crystals are recrystallized from water. 92 g. of colorless 4-methoxy-L-m-tyrosine of melting point 251°-252°C. are obtained. $[\alpha]_D^{25} = -34.2^\circ$ (c = 1 percent in water).

EXAMPLE 22

By the procedure described in Examples 1 and 2, 4-methoxy-L-m-tyrosine is obtained from N,O-diacyl-4-methoxy-L-m-tyrosine.

EXAMPLE 23

Dry hydrogen chloride gas is introduced over a period of 1 hour into a suspension of 25 g. of 4-methoxy-L-m-tyrosine in 300 ml. of absolute methanol, the temperature rising to about 50°C. and the 4-methoxy-L-m-tyrosine gradually passing into solution. The solution is then left at room temperature for 72 hours and subsequently evaporated at 12 mm Hg. with the addition of 100 ml. of absolute toluene.

The crystalline residue obtained is dissolved in 100 ml. of ice water and 30 ml. of a saturated aqueous potassium carbonate solution are added to the solution. The mixture is then extracted twice with 200 ml. of ethyl acetate each time and the combined organic extracts are dried over sodium sulphate and concentrated at 12 mm Hg. The residue is crystallized from ethyl acetate/diethyl ether to yield 22.6 g. of 4-methoxy-L-m-tyrosine methyl ester as colorless crystals of melting point 81°-83°C. $[\alpha]_D^{22} = +22.8$ (c = 1 percent in methanol).

EXAMPLE 24

2.25 g. of 4-methoxy-D,L-m-tyrosine methyl ester (prepared from 4-methoxy-D,L-m-tyrosine by the procedure described in Example 8 melting point 63°-64°C.) are heated on a steam-bath together with 3 g. of L-tartaric acid 2,4-dichloroanilide in 15 ml. of isopropanol. The clear solution obtained is cooled and an oily precipitate then separates out. The supernatant solution is decanted, digested with acetonitrile. Crystallization occurs and the crystals are recrystallized twice from acetonitrile/methanol. The crystals obtained (the salt of 4-methoxy-D,L-m-tyrosine methyl ester with L-tartaric acid 2,4-dichloroanilide) are suspended in 100 ml. of ethyl acetate. The suspension is shaken with 50 ml. of saturated aqueous sodium carbonate solution. The aqueous phase is separated and again washed with 50 ml. of ethyl acetate. The organic phases are combined, dried over sodium sulphate and evaporated under reduced pressure. The residue obtained is recrystallized from ethyl acetate/diethyl ether to yield 4-methoxy-L-m-tyrosine methyl ester of melting point 79°-81°C. $[\alpha]_D^{22} = +19.4^\circ$ (c = 1 percent in methanol).

The following Examples illustrated typical pharmaceutical preparations containing the phenethylamine derivatives provided by the invention:

EXAMPLE 25

Tablets of the following composition are manufactured in the usual manner:

4-methoxy-L-m-tyrosine	500	mg.
cellulose preparation "AVICEL"	147.3	mg.
maize starch	40	mg.
methyl cellulose	10	mg.
magnesium stearate	5	mg.

EXAMPLE 26

A hard gelatin capsule, from which the active ingredient is released with delay after the release of a decarboxylase inhibitor, can be manufactured as follows:

A core consisting of 50 mg. of 4-methoxy-L-m-tyrosine, 8 mg. of maize starch, 15 mg. of lactose, 1.8 mg. of talc and 0.2 mg. of magnesium stearate is coated with a cellulose acetate phthalate varnish in order to make it resistant to gastric juice.

A granulate is manufactured from 50 mg. of N¹-L-serine-N²-(2,3,4-trihydroxybenzyl)-hydrazide hydrochloride, 5.8 mg. of mannitol and 2.4 mg. of polyvinylpyrrolidone in the usual manner.

The coated core and the granulate are introduced into a hard gelatin capsule.

We claim:

1. The L-antipode of the formula:

wherein R is hydrogen or lower alkyl group; or pharmaceutically acceptable salts thereof.

2. The antipode of claim 1 wherein R is hydrogen.

3. The antipode of claim 2 wherein said antipode is 4-methoxy-L-m-tyrosine hydrochloride.

4. The antipode of claim 2 wherein said antipode is 4-methoxy-L-m-tyrosine.

5. The antipode of claim 1 wherein R is lower alkyl.

6. The antipode of claim 5 wherein said antipode is 4-methoxy-L-m-tyrosine methyl ester.

7. The L-antipode of the formula:

wherein R₁ is loweralkanoylamino or formylamino; R₂' is formyloxy or lower alkanoyloxy; R₃ is carboxy or carboxyloxy.

8. The antipode of claim 7 wherein said antipode is N-acetyl 3-(3-formyloxy-4-methoxy phenyl)-L-alanine methyl ester.

9. The antipode of claim 1 wherein said antipode is N,O-diacyl-4-methoxy-L-m-tyrosine.

10. The antipode of claim 7 wherein said antipode is N-acetyl-3-(3-formyloxy-4-methoxy phenyl)-L-alanine.

11. The antipode of claim 7 wherein said antipode is N,O-diacyl-4-methoxy-L-m-tyrosine ethyl ester.

12. The antipode of claim 7 wherein said antipode is O-acetyl-N-formyl-4-methoxy-L-m-tyrosine.

13. An L-antipode of the formula:

wherein R₁ is formylamino or loweralkanoylamino; R₂' is formyl or lower alkanoyl; and R₃ is carboxy or lower alkanoyloxy.

15

14. The antipode of claim 13 wherein said antipode is N-acetyl-3-(3-formyl-4-methoxy phenyl)-L-alanine methyl ester.

15. The antipode of claim 13 wherein said antipode is N-acetyl-3-(3-formyl-4-methoxy phenyl)-L-alanine ethyl ester.

16

16. The antipode of claim 13 wherein said antipode is N-acetyl-3-(3-acetyl-4-methoxy phenyl)-L-alanine.

17. The antipode of claim 13 wherein said antipode is 3-(3-acetyl-4-methoxy phenyl)-N-formyl-L-alanine.
